[57] CLAIM

The ornamental design for a container with flying toy lid, as shown and described.

DESCRIPTION

FIG. 1 is a perspective view of a container with flying toy lid, showing my new design;

FIG. 2 is an exploded perspective view thereof; and,

FIG. 3 is a sectional view thereof, taken on the plane 3—3 in FIG. 2, showing top and bottom surface contours.

FIG. 1**FIG. 3**

FIG. 2
